(57) **CLAIM**

The ornamental design for a “tire,” as shown and described.

DESCRIPTION

FIG. 1 is a perspective view of a tire of the present application taken from the front and a right side thereof; FIG. 2 is a front view thereof; it being understood that the tread pattern is repeated throughout the circumference of the tire;

FIG. 3 is a right side view thereof; and,
FIG. 4 is an enlarged front elevation view of FIG. 2, showing a portion thereof.

The broken line showing of a side wall region is for the purpose of illustrating portions of the tire and forms no part of the claimed design.
